UNITED STATES PATENT OFFICE

2,424,183

RESILIENT HOLDING MEANS FOR STRAW
PACKAGING MACHINESPaul C. Moore, Jr., Baltimore, Md., assignor to
Maryland Paper Products Company, Inc., Baltimore, Md., a corporation of Maryland

Application June 19, 1946, Serial No. 677,762

5 Claims. (Cl. 93—3)

1

The present invention relates to machines which form a continuous tubular envelope, sever the same into sections of predetermined length, deliver the cut sections as individual wrappers to a catcher which deposits the wrappers onto a rotary wrapper receiver which carries the wrappers past a loading device that injects a straw or straws endwise into the wrapper while the wrapper is held by the loading device against an abutment endwise.

The invention seeks to improve the machine disclosed in the Toolan Patent No. 2,146,490 of February 7, 1939.

More particularly, the invention seeks to provide an improved means to hold the straws centered in the wrapper as soon as they shall have been placed therein by the loading device and while the loading device is being withdrawn from the filled wrapper.

Further, the invention seeks to provide an improvement in the straw-carrying slide attachment that engages the end of the wrapper through which end the straw or straws are inserted, the more effectively to serve its intended purpose.

Other objects will in part be obvious and in part will be pointed out hereinafter.

To the attainment of the aforesaid objects and ends the invention further resides in the novel details of construction, combinations and arrangements of parts, all of which will be first fully described and will then be specifically pointed out in the appended claims, reference being had to the accompanying drawings in which—

Fig. 1 is a top plan view of a portion of a straw packaging machine to which my invention has been applied.

Figs. 2 and 3 are detail cross sections of the same on the line 2—2 of Fig. 1, showing two different positions of the parts in their cycle of operation.

Fig. 4 is a view similar to Figs. 2 and 3 but taken on the line 4—4 of Fig. 1.

Fig. 5 is a plan view of one of the wrapper-engaging socket members carried by the push-bars.

Fig. 6 is a section on the line 6—6 of Fig. 5.

Fig. 7 is a rear elevation of the same.

Fig. 8 is a front elevation of the same.

Fig. 9 is a view similar to Fig. 6, showing another form of a wrapper-engaging member.

Fig. 10 is a front elevation of the same.

In the drawings, in which like numerals and letters of reference indicate like parts in all the figures, 1 is the bed of the machine on which, in suitable bearings 2, is mounted the main rotat-

2

able shaft 3 which carries the rotatable straw carrier composed of two spiders having bifurcated arms 5 that extend radially from the hubs 4 and carry wrapper receiving members 6, there being two such members 6 spaced apart as at 7. Each member 6 has a groove 8 into which the wrappers are placed by a wrapper-catching device of any approved construction, preferably that disclosed in the application for patent filed June 14, 1946, Ser. No. 676,759, by John B. West. Such catching device includes two catchers 9 which operate in the spaces 7 and are carried by a rod 10 that is carried by one arm 11 of a lever that is pivoted on a stationary shaft 12 held in suitable supports 13. The other arm 14 carries a roller 15 to cooperate with a cam 16 on a continuously rotating shaft 17, in order to lower the catchers from a wrapper-receiving position, Fig. 4, to a wrapper-depositing position, Fig. 3. A return spring 24 restores the catchers to a normal or wrapper-receiving position. The shaft 12 also supports curved fingers 18 which cooperate with the filled-package-discharging members 19.

Wrapper restraining guides 20 keep centrifugal force from dislodging the wrappers from the wrapper carrier. An abutment plate 21 prevents the wrappers from being pushed back, while being filled, beyond a predetermined distance and lines up the wrappers in the carrier.

The foregoing parts, not being of my invention, need not be described in detail as I make no claim thereto per se.

The machines which I have improved also include a straw hopper 22 and a wrapper-loading mechanism which includes straw-carrying slide bars 23 into which the straws are deposited from the hopper and from which the straws are pushed by push bars into the wrappers via suitable fittings 26.

The hopper mechanism, the slide bars and their operating mechanism, and the push bars and their operating mechanism may, generically, be the same as are shown in the Toolan patent aforesaid. However, the fittings 26 through 45 which the straws are passed into the wrappers and by which the wrappers are held against the abutment plate in the present case, are of my invention and are best shown in Figs. 5 et seq., by reference to which and to Fig. 1 it will be seen

that the wrapper-engaging member 26 includes a bell portion 27 on the front upright portion 28. The portions 27 and 26 have a passage through the same whose cross-sectional shape is either elliptic (Figs. 5 to 8 inclusive) or round (Figs. 9 and 10), accordingly as two straws or one straw

are to be placed in a wrapper. The entrance part of the passage is tapered as shown and a shoulder **30** is provided against which the wrapper end abuts previous to receiving the straws (see dotted end *w*, Fig. 6). Countersunk holes **31** are provided to receive the attaching screws **25**. The portion **28** is also bell mounted as at **29** to facilitate the entrance of the straw or straws into the passage through portions **28** and **27**.

In Figs. 9 and 10 those parts which correspond to like parts in Figs. 5 to 8 inclusive bear the same reference number plus the index letter *a*, and need not be further described.

The cam shaft **32** operates the wrapper severing mechanism **33** and the mechanism **34** which crimps the longitudinal fold of the paper strip together and feeds the continuous wrapper forwardly, while the end-sealing crimping rollers **35** are operated by the separate shaft **17**. The mandrel on which the continuous wrapper tube is formed is indicated by **39**. The same not being my invention, no claim thereto is made by me.

In the Toolan machine aforesaid a pivoted finger (**204**, Fig. 13 of that patent) was used to hold the packaged straws while the funnel members were being withdrawn. This finger device has not proven satisfactory in use and did not always prevent the straws and wrappers from getting out of alignment in the rotary carrier, with the result that sometimes the package ends were improperly crimp-sealed. I have therefore improved this part of the machine by providing thin resilient wires **36** whose ends are threaded loosely through studs **37** and their ends bent over as at **38**. The studs are so located (Figs. 2, 3, and 4) that the wires normally lie across the curve of the fixed guides **20** as cords of an arc. Thus when the members **9** reach the position at the bottom of Fig. 3 the filled wrappers engage wires **36**, which holds the wrappers and straws together in the grooves **8**.

As the wires preferably lie in vertical planes that pass between the members **6** of the spiders, they will not engage those members but only the packages adjacent to the outer (left-right) members **6** of the spiders, and hence will firmly hold the packages seated in the members **6** while the straw push rods and fittings **26** are being drawn back from the same. The wires, being of light construction and loosely held, will not exert sufficient pressure to cut into the wrappers or effect a bend therein, and their use has eliminated both the pivoted finger method (Toolan specification, page 2, column 2, line 67 to page 3, lines 1 to 11) and the vacuum method (Toolan specification, page 3, lines 12 to 37 inclusive) of the Toolan machine, and gives better results than either of said methods.

From the foregoing description, taken in connection with the accompanying drawings, it is thought that the construction, operation, and advantages of my improvements will be clear to those skilled in the art.

What I claim is:

1. In a straw packaging machine wherein are provided rotatable wrapper carriers and arcuate guides cooperatively associated with the same: the improvement which comprises resilient wires carried by said arcuate guides and projecting across the path of the wrapper carriers at predetermined places for purposes described.

2. In a straw packaging machine wherein are provided a rotatable body having wrapper receiving and carrying members and arcuate guide

plates cooperatively associated with said body to prevent the wrappers and contents from falling out of said carrying members as the said body rotates: the improvement which comprises flexible resilient elements normally held across the paths of said carrying members for holding the wrappers when filled with straws in said carrying members at a predetermined place in their paths of travel.

3. In a straw packaging machine wherein are provided a rotatable shaft, a pair of spiders secured to said shaft and spaced apart, each spider having arms, each arm having a pair of spaced-apart wrapper-carrying elements, arcuate guide plates operatively associated with each spider for loosely holding the wrappers and their contents in said carrying elements, and means to hold the wrappers against endwise movement while being filled: the improvement which combines flexible resilient elements with said guide plates for snugly holding wrappers and their contents together firmly in said carrying elements after the wrappers have been filled and before they are removed from the carrying elements.

4. In a straw packaging machine wherein are provided wrapper-receiving means, straw-receiving means, means to deliver straws from said straw-receiving means into the wrappers on said wrapper-receiving means, said last named means including wrapper-end-engaging slide members and an abutment plate and straw pushers for pushing straws into the wrappers on said wrapper-receiving means, and fixed annular guides for loosely holding the wrappers and their contents in place on said wrapper-receiving means: the improvement which resides in combining with the aforesaid structure resilient flexible elements located at the position where the straws are placed fully into the wrappers and the slides and pushers are about to be withdrawn for holding wrappers and straws firmly in place in the wrapper-receiving means while the slide members and pushers are being withdrawn.

5. In a straw packaging machine wherein are provided wrapper-receiving means, straw-receiving means, means to deliver straws from said straw-receiving means into the wrappers on said wrapper-receiving means, said last named means including wrapper-end-engaging slide members and an abutment plate and straw pushers for pushing straws into the wrappers on said wrapper-receiving means, and fixed annular guides for loosely holding the wrappers and their contents in place on said wrapper-receiving means: the improvement which resides in combining with the aforesaid structure resilient flexible elements located at the position where the straws are placed fully into the wrappers and the slides and pushers are about to be withdrawn for holding wrappers and straws firmly in place in the wrapper-receiving means while the slide members and pushers are being withdrawn, said flexible resilient elements comprising wires carried by said fixed annular guides.

65 PAUL C. MOORE, JR.
